8 Claims

ABSTRACT OF THE DISCLOSURE

Compounds of the formula

where R_1 is lower alkyl and R_2 and R_3 are lower alkyl, phenyl, alkyl phenyl or chlorophenyl are prepared by (1) reacting alkyl vinyl ethers with phosphorus pentachloride, (2) converting the complex to alkoxy 2-chloroethyl phosphonyldichloride by treatment with sulfur dioxide with simultaneous dehydrohalogenation to alkoxyvinylphosphonyldichloride and (3) reacting with two moles of a mercaptan in the presence of a tertiary amine. The new compounds are useful as pre- and post-emergent herbicides. S,S - diisopropyl - 2 - isobutoxyvinylphosphonodithioate was the overall best herbicide tested.

The present invention is related to the invention in Regel et al. application 596,412, filed Nov. 23, 1966, now Patent No. 3,416,912 wherein 2-alkylthiovinyphosphonodithioates were prepared and found to have herbicidal activity.

The present invention relates to substituted vinylphosphonodithioates.

It is an object of the invention to prepare novel substituted vinyl phosphonodithioates.

Another object is to develop novel herbicides.

An additional object is to prepare herbicides having selective pre-emergent herbicidal activity.

A further object is to prepare herbicides having selective post-emergent herbicidal activity.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

It has now been found that these objects are obtained by preparing compounds having the formula:

and applying them as pre- and post-emergent herbicides.

In the formulae R_1 is lower alkyl, e.g. of 1 to 8 carbon atoms, most preferably of 1 to 4 carbons, R_2 and R_3 are alkyl of 1 to 8 carbons, phenyl, lower alkyl phenyl or chlorophenyl, R_2 and R_3 can be the same or different.

2

Preferably R_2 and R_3 are lower alkyl, most preferably having 2 to 3 carbon atoms. The most preferred compound tested was S,S-diisopropyl-2-isobutoxyvinylphosphonodithioate and it possessed both high pre- and post-emergent herbicidal activity.

Other compounds within the present invention include S,S-diethyl-2-methoxyvinylphosphonodithioate, S,S-diisopropyl-2-methoxyvinylphosphonodithioate, S,S-dimethyl-2-ethoxyvinylphosphonodithioate, 10 S,S-diethyl-2-ethoxyvinylphosphonodithioate, S,S-dipropyl-2-ethoxyvinylphosphonodithioate, S,S-diisopropyl-2-ethoxyvinylphosphonodithioate, S,S-dibutyl-2-ethoxyvinylphosphonodithioate, S,S-diphenyl-2-ethoxyvinylphosphonodithioate, 15 S,S-diethyl-2-isobutoxyvinylphosphonodithioate, S,S-dibutyl-2-isobutoxyvinylphosphonodithioate, S,S-dimethyl-2-methoxyvinylphosphonodithioate, S,S-dimethyl-2-propoxyvinylphosphonodithioate, S,S-dimethyl-2-isopropoxyvinylphosphonodithioate, 20 S,S-dimethyl-2-butoxyvinylphosphonodithioate, S,S-dimethyl-2-sec. butoxyvinylphosphonodithioate, S-methyl-S-propyl-2-isobutoxyvinylphosphonodithioates, S,S-diethyl-2-isoamyl-oxoxyvinylphosphonodithioate, S,S-diethyl-2-octoxyvinylphosphonodithioate, 25 S,S-dipropyl-2-methoxyvinylphosphonodithioate, S,S-dibutyl-2-methoxyvinylphosphonodithioate, S,S-di sec. butyl-2-methoxyvinylphosphonodithioate, S,S-diamyl-2-methoxyvinylphosphonodithioate, S,S-diethyl-2-methoxyvinylphosphonodithioate, 30 S,S-diphenyl-2-methoxyvinylphosphonodithioate, S,S-di p-tolyl-2-methoxyvinylphosphonodithioate, S,S-di o-tolyl-2-methoxyvinylphosphonodithioate, S,S-di p-butylphenyl-2-methoxyvinylphosphonodithioate, S,S-di p-chlorophenyl-2-methoxyvinylphosphonodithioate, 35 S-ethyl-S-p-chlorophenyl-2-methoxyvinylphosphonodithioate, S-ethyl-S-propyl-2-ethoxyvinylphosphonodithioate, S-propyl-S-butyl-2-ethoxyvinylphosphonodithioate, S,S-diamyl-2-ethoxyvinylphosphonodithioate, 40 S,S-dihexyl-2-ethoxyvinylphosphonodithioate, S,S-dicyclohexyl-2-ethoxyvinylphosphonodithioate, S,S-diheptyl-2-ethoxyvinylphosphonodithioate, S,S-diphenyl-2-ethoxyvinylphosphonodithioate, S,S-di o-chlorophenyl-2-ethoxyvinylphosphonodithioate, 45 S,S-diethyl-2-propoxyvinylphosphonodithioate, S,S-dipropyl-2-propoxyvinylphosphonodithioate, S,S-dibutyl-2-propoxyvinylphosphonodithioate, S,S-dihexyl-2-propoxyvinylphosphonodithioate, S,S-diisooctyl-2-propoxyvinylphosphonodithioate, 50 S,S-di m-tolyl-2-propoxyvinylphosphonodithioate, S,S-dipropyl-2-isopropoxyvinylphosphonodithioate, S,S-disopropyl-2-isopropoxyvinylphosphonodithioate, S,S-dibutyl-2-isopropoxyvinylphosphonodithioate, S,S-diethyl-2-butoxyvinylphosphonodithioate, 55 S,S-dihexyl-2-butoxyvinylphosphonodithioate, S,S-diamyl-2-isobutoxyvinylphosphonodithioate, S,S-di(2',4'-dichlorophenyl)-2-isobutoxyvinylphosphonodithioate.

The compounds of Formula I are readily prepared by reacting an alkyl vinyl ether with phosphorus pentachloride preferably dissolved in a solvent such as carbon tetrachloride to form the 2-alkoxy-2-chloroethylphosphonyldichloride. The complex is treated with two moles of sulfur dioxide. Dehydrohalogenation of the intermediate formed in this reaction occurs simultaneously or upon removal of the phosphorus oxychloride-thionylchloride-solvent mixture to yield alkoxyvinylphosphonyldichloride. The alkoxyvinylphosphonodithioates are formed by esterification of the alkoxyvinylphosphonyldichloride with a mercaptan in the presence of a tertiary amine, e.g. triethylamine, tripropylamine, N,N-

dimethylaniline, etc. The equations for the series of reactions is as follows:

As alkyl vinyl ethers as starting materials there can be employed methyl vinyl ether, ethyl vinyl ether, propyl vinyl ether, isopropyl vinyl ether, n-butyl vinyl ether, isobutyl vinyl ether, sec. butyl vinyl ether, amyl vinyl ether, isoamyl vinyl ether, hexyl vinyl ether, octyl vinyl ether, isoctyl vinyl ether.

As mercaptans there can be used methyl mercaptan, ethyl mercaptan, propyl mercaptan, isopropyl mercaptan, butyl mercaptan, isobutyl mercaptan, hexyl mercaptan, cyclohexyl mercaptan, amyl mercaptan, heptyl mercaptan, octyl mercaptan, isoctyl mercaptan, 2-ethylhexyl mercaptan, thiophenol, p-methylthiophenol, 2-chlorothiophenol, 2,4-dichlorothiophenol, 4-butylthiophenol.

Unless otherwise indicated all parts and percentages are by weight.

EXAMPLE 1

29 grams (0.5 mole) of methyl vinyl ether was added to a stirring suspension of 208 grams (1 mole) of phosphorus pentachloride in 8-10 volumes of carbon tetrachloride. The reaction mixture was cooled to 10-20° C. throughout the addition. After the addition was completed, the reaction mixture was allowed to warm to room temperature (25° C.) and was then stirred for 12-14 hours.

Gaseous sulfur dioxide was then bubbled into the stirring suspension at a rapid rate. Cooling was maintained at 10-20° C. throughout the addition. Completion of the reaction was evidenced by disappearance of the solid phase and the formation of a clear solution. The 2-methoxyvinyl phosphonyl dichloride was obtained by direct distillation of the reaction mixture, B.P. 0.4 85° C.; n_{D}^{25} 1.4997; yield 85%.

EXAMPLE 2

144 grams (2 moles) of ethyl vinyl ether was added dropwise to a stirring suspension of 833 grams (4 moles) of phosphorus pentachloride in 8-10 volumes of carbon tetrachloride. The reaction mixture was cooled to 10-20° C. throughout the addition. After the addition was completed, the reaction mixture was allowed to warm to room temperature and then stirred for 12-14 hours.

Gaseous sulfur dioxide was then bubbled into the stirring suspension at a rapid rate. Cooling was maintained at 10-20° C. throughout the addition. Completion of the reaction was evidenced by the disappearance of the solid phase and the formation of a clear solution. The 2-ethoxyvinyl phosphonyl dichloride was obtained by direct distillation of the reaction mixture, B.P. 27 142° C.; n_{D}^{25} 1.4950; yield 75%.

EXAMPLE 3

100 grams (1 mole) of isobutyl vinyl ether was added dropwise to a stirring suspension of 417 grams (2 moles) of phosphorus pentachloride in 8-10 volumes of carbon tetrachloride. The reaction mixture was cooled to 10-20° C.

C. throughout the addition. After the addition was completed, the reaction mixture was allowed to warm to room temperature (25° C.) and then stirred for 12-14 hours.

Gaseous sulfur dioxide was then bubbled into the stirring suspension at a rapid rate. Cooling was maintained at 10-20° C. throughout the addition. Completion of the reaction was evidenced by the disappearance of the solid phase and the formation of a clear solution.

The 2-isobutoxyvinylphosphonyldichloride was obtained by direct distillation of the reaction mixture, B.P. 0.15 92° C.; n_{D}^{20} 1.4868; yield 72%.

EXAMPLE 4

17.5 grams (0.1 mole) of 2-(methoxy)vinyl phosphonyl dichloride was diluted with 10 volumes of dry benzene. 12.5 grams (0.2 mole) of ethyl mercaptan was then added. 20.2 grams (0.2 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. (If the water wash was acid, as occurred in some experiments, the benzene layer was extracted with 5% sodium bicarbonate solution. The benzene layer was then further washed until all washes were neutral.) The benzene layer was then dried over anhydrous sodium sulfate. The solvent was stripped in vacuo on a steam bath; and the resulting crude oil was distilled to obtain S,S-diethyl-2-methoxyvinylphosphonodithioate (Compound 7374) as the product. B.P. 0.05 115° C.; n_{D}^{25} 1.5529; yield=67%.

EXAMPLE 5

13.5 grams (0.08 mole) of 2-(methoxy)vinyl phosphonyl dichloride was diluted with 10 volumes of dry benzene. 12.5 grams (0.16 mole) of isopropyl mercaptan was then added. 15.2 grams (0.15 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. (If the water wash was acid, as occurred in some experiments, the benzene layer was extracted with 5% sodium bicarbonate solution. The benzene layer was then further washed until all washes were neutral.) The benzene layer was then dried over anhydrous sodium sulfate. The solvent was stripped in vacuo on a steam bath; and the resulting crude oil was distilled to obtain S,S-diisopropyl-2-methoxyvinylphosphonodithioate (Compound 7375) as the product.

B.P. 0.08 117° C.; n_{D}^{18} 1.5340; yield=75%

EXAMPLE 6

19 grams (0.1 mole) of 2-(ethoxy)vinyl phosphonyl dichloride was diluted with 10 volumes of dry benzene. 11.5 grams (0.24 mole) of methyl mercaptan was then added. 20.2 grams (0.2 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. The benzene layer was then dried over anhydrous sodium sulfate. The solvent was stripped in vacuo on a steam bath; and the resulting crude oil was distilled to obtain S,S-dimethyl-2-ethoxyvinylphosphonodithioate (Compound 7579) as the product.

B.P. 0.05 125° C.; n_{D}^{20} 1.5456; yield=94%

EXAMPLE 7

19 grams (0.1 mole) of 2-(ethoxy) vinyl phosphonyl dichloride was diluted with 10 volumes of dry benzene. 12.5 grams (0.2 mole) of ethyl mercaptan was then added. 20.2 grams (0.2 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. The benzene layer was then dried over anhydrous sodium sulfate. The solvent was stripped in vacuo on a steam bath; and the resulting crude oil was distilled to obtain S,S - diethyl - 2 - ethoxyvinylphosphonodithioate (Compound 7576) as the product.

B.P._{0.1} 126° C.; n_D^{20} 1.5456; yield=94%

EXAMPLE 8

19 grams (0.1 mole) of 2-(ethoxy)vinyl phosphonyl dichloride was diluted with 10 volumes of dry benzene. 16 grams (0.22 mole) of 1-propanethiol was then added. 20.2 grams (0.2 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. The benzene layer was then dried over anhydrous sodium sulfate. The solvent was stripped in vacuo on a steam bath; and the resulting crude oil was distilled to obtain S,S - dipropyl - 2 - ethoxyvinylphosphonodithioate (Compound 7577) as the product.

B.P._{0.05} 136° C.; n_D^{20} 1.5341; yield=97%

EXAMPLE 9

19 grams (0.1 mole) of 2-(ethoxy)vinyl phosphonyl dichloride was diluted with 10 volumes of dry benzene. 16.7 grams (0.22 mole) of 2-propanethiol was then added. 20.2 grams (0.2 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. The benzene layer was then dried over anhydrous sodium sulfate. The solvent was stripped in vacuo on a steam bath; and the resulting crude oil was distilled to obtain S,S-diisopropyl-2-ethoxyvinylphosphonodithioate (Compound 7578) as the product.

B.P._{0.02} 115° C.; n_D^{20} 1.5269; yield=75%

EXAMPLE 10

19 grams (0.1 mole) of 2-(ethoxy)vinyl phosphonyl dichloride was diluted with 10 volumes of dry benzene. 18.5 grams (0.2 mole) of 1-butanethiol was then added. 20.2 grams (0.2 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. The benzene layer was then dried over anhydrous sodium sulfate. The solvent was stripped in vacuo on a steam bath; and the resulting crude oil was distilled to obtain S,S - dibutyl - 2 - ethoxyvinyl phosphonodithioate (Compound 7580) as the product. B.P._{0.05} 147° C.; n_D^{20} 1.5251; yield=92%.

EXAMPLE 11

19 grams (0.1 mole) of 2-(ethoxy)vinyl phosphonyl dichloride was diluted with 10 volumes of dry benzene.

75

24 grams (0.22 mole) of thiophenol was then added. 20.2 grams (0.2 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. The benzene layer was then dried over anhydrous sodium sulfate. The solvent was stripped in vacuo on a steam bath; and the resulting crude oil was distilled to obtain S,S - diphenyl - 2 - ethoxyvinylphosphonodithioate (Compound 7604) as the product. M.P. 82° C.; yield=98%.

EXAMPLE 12

21.7 grams (0.1 mole) of 2-(isobutoxy)vinyl phosphonyl dichloride was diluted with 10 volumes of dry benzene. 13.7 grams (0.22 mole) of ethyl mercaptan was then added. 20.2 grams (0.2 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. The benzene layer was then dried over anhydrous sodium sulfate. The solvent was stripped in vacuo on a steam bath; and the resulting crude oil was distilled to obtain S,S-diethyl - 2 - isobutoxyvinylphosphonodithioate (Compound 7675) as the product. n_D^{20} 1.5291; yield=90%.

EXAMPLE 13

21.7 grams (0.1 mole) of 2-(isobutoxy)vinyl phosphonyl dichloride was diluted with 10 volumes of dry benzene. 16 grams (0.22 mole) of 2-propanethiol was then added. 20.2 grams (0.2 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. The benzene layer was then dried over anhydrous sodium sulfate. The solvent was stripped in vacuo on a steam bath; and the resulting crude oil was distilled to obtain S,S-diisopropyl - 2 - isobutoxyvinylphosphonodithioate (Compound 7676) as the product. B.P._{0.6} 145° C.; n_D^{20} 1.5226; yield=91%.

EXAMPLE 14

10.9 grams (0.05 mole) of 2-(isobutoxy)vinyl phosphonyl dichloride was diluted with 10 volumes of dry benzene. 10 grams (0.11 mole) of 1-butanethiol was then added. 10.1 grams (0.1 mole) of triethylamine was added to this stirring solution at such a dropwise rate to keep the exothermic reaction temperature at 30-35° C. After the addition was completed, the reaction mixture was allowed to stir until room temperature was reached (25° C.).

The reaction mixture was then washed with cold water. The benzene layer was then dried over anhydrous sodium sulfate. The solvent was stripped in vacuo on a steam bath; and the resulting crude oil was distilled to obtain S,S-dibutyl - 2 - isobutoxyvinylphosphonodithioate (Compound 7677) as the product. n_D^{20} 1.5142; yield=93%.

The herbicides of the present invention can be used alone or they can be applied together with inert solids to form dusts, or can be dispersed in a suitable liquid dilute, e.g. organic solvents or water.

There can also be added surface active agents or wetting agents and/or inert solids in the liquid formulations. In such case, the active ingredients can be from 0.01 to 95% by weight of the entire composition.

As organic solvents there can be employed hydrocarbons, e.g. benzene, toluene, xylene, kerosene, diesel fuel, fuel oil and petroleum naphtha, ketones such as acetone,

methyl ethyl ketone and cyclohexanone, chlorinated hydrocarbons such as carbon tetrachloride, chloroform, trichloroethylene, and perchloroethylene, esters such as ethyl acetate, amyl acetate and butyl acetate, ethers, e.g. ethylene glycol monomethyl ether and diethylene glycol monomethyl ether, alcohols, e.g. methanol, ethanol, isopropanol, amyl alcohol, ethylene glycol, propylene glycol, butyl carbitol acetate and glycerine. Mixtures of water and organic solvents, either as solutions or emulsions, can be employed.

The novel herbicides can also be applied as aerosols, e.g. by dispersing them in air by means of a compressed gas such as dichlorodifluoromethane or trichlorofluoromethane and other Freons and Genetrons, for example.

The pesticides of the present invention can also be applied with adjuvants or carriers such as talc, pyrophyllite, synthetic fine silica, attapulgus clay, kieselguhr, chalk, diatomaceous earth, lime, calcium carbonate, bentonite, Fuller's earth, cottonseed hulls, wheat flour, soybean flour, pumice, tripoli, wood flour, walnut shell flour, redwood flour and lignin.

As stated, it is frequently desirable to incorporate a surface active agent in the herbicidal compositions of the present invention. Such surface active or wetting agents are advantageously employed in both the solid and liquid compositions. The surface active agent can be anionic, cationic or nonionic in character.

Typical classes of surface active agents include alkyl sulfonate salts, alkylarylsulfonate salts, alkylarylpoly-

taurate, Turkey red oil, sodium dibutyl naphthalene sulfonate, sodium lignin sulfonate, polyethylene glycol stearate, sodium dodecylbenzene sulfonate, tertiary dodecyl polyethylene glycol thioether (Nonionic 218), long chain ethylene oxide-propylene oxide condensation products, e.g. Pluronic 61 (molecular weight 1000), polyethylene glycol ester of tall oil acids, sodium octyl phenoxyethoxyethyl sulfate, tris (polyoxyethylene) sorbitan monostearate (Tween 60), and sodium dihexyl sulfosuccinate.

The compounds of the present invention were tested as pre-emergent herbicides at the indicated dosages against the indicated plants. In this test the surface of the soil was sprayed with an acetone solution of the test compound the same day as the seeds were planted. The flats which were planted were 14 inches long, 10 inches wide and 3.5 inches deep. 3 grams of the test material was diluted to 30 ml. with acetone. Each ml. of this solution when applied to the flat was equivalent to 1 lb./acre of test material (active ingredient). The requisite number of ml. of the acetone solution was diluted to 40 ml. and this diluted mixture was sprayed on the flats, e.g. for 15 lbs./acre 15 ml. of the original acetone solution was diluted to 40 ml. with acetone and for 5 lbs./acre 5 ml. of the original acetone solution was diluted to 40 ml. with acetone. In the pre-emergent herbicide test the results are expressed on a 0-10 scale with 0 indicating no effect and 10 indicating complete inhibition of seeds to germinate and emerge. The results in the pre-emergent herbicide are set forth in Table 1.

ether alcohols, fatty acid esters of polyhydric alcohols and the alkylene oxide addition products of such esters, and addition products of long chain mercaptans and alkylene oxides. Typical examples of such surface active agents include the sodium alkylbenzene sulfonates having 10 to 18 carbon atoms in the alkyl group, alkylphenol ethylene oxide condensation products, e.g. p-isooctylphenol condensed with 10 ethylene oxide units, soaps, e.g. sodium stearate and potassium oleate, sodium salt of propyl-naphthalene sulfonic acid, di (2-ethylhexyl) ester of sodium sulfosuccinic acid, sodium lauryl sulfate, sodium decane sulfonate, sodium salt of the sulfonated monoglyceride of cocoanut fatty acids, sorbitan sesquioleate, lauryl trimethyl ammonium chloride, octadecyl trimethyl ammonium chloride, polyethylene glycol lauryl ether, polyethylene glycol esters of fatty acids and rosin acids, e.g. Ethofat 7 and 13, sodium N-methyl-N-oleyl

60 The 2-alkoxyvinylphosphonodithioates possessed high pre-emergent herbicidal activity on certain broad leaf weeds, as represented in the tests by pigweed and sugar beets, as well as on grassy weeds such as watergrass.

65 S,S-diisopropyl - 2 - methoxyvinylphosphonodithioate (Compound 7375), S,S-diethyl-2-ethoxyvinylphosphonodithioate (Compound 7576), S,S-di-n-propyl-2-ethoxyvinylphosphonodithioate (Compound 7577) and S,S-diisopropyl - 2 - ethoxyvinylphosphonodithioate (Compound 7578) were especially active and showed selectively 70 among grasses. S,S-diisopropyl - 2 - isobutoxyvinylphosphonodithioate (Compound 7676) also showed good pre-emergent herbicidal activity and also exhibited selectivity.

75 The compounds of the present invention also are useful as post-emergent herbicides. The test compounds

were dissolved in acetone in the same manner as in the pre-emergent herbicide tests. The flats, however, were sprayed 10 to 14 days after planting and the herbicidal activity was observed one week after the application of the test compound. The results are set forth in Table 2. 5

TABLE 2

Compound	Lbs. AI per acre	Pigweed	Wild mustard	Sugar beets	Morning glory	Water- grass	Millet	Johnson grass
7375-----	8	10	7	9	0	7	5	-----
	2	10	6	9	-----	7	6	-----
7577-----	8	9	7	8	9	7	7	-----
	2	1	2	0	3	3	1	-----

7677-----	8	10	10	-----	10	9	9	7
	2	10	8	-----	9	8	8	7

All of the compounds tested showed high post-emergent herbicidal activity at the 8 lb./acre rate. S,S-diisopropyl-2-methoxyvinylphosphonodithioate (Compound 7375), S,S - diisopropyl - 2 - isobutoxyvinylphosphonodithioate (Compound 7676) and S,S-dibutyl-2-isobutoxyvinylphosphonodithioate (Compound 7677) possessed high activity even at the 2 lb./acre level. 25

The most preferred compound for overall pre- and post-emergent herbicidal activity was Compound 7676.

What is claimed is:

1. A process of killing plants comprising applying to the plant habitat a herbicidally effective amount of a compound having the formula

where R_1 is lower alkyl and R_2 and R_3 are selected from the group consisting of alkyl of 1 to 8 carbon atoms, phenyl, lower alkyl phenyl and chlorophenyl. 45

2. A process according to claim 1 wherein the compound is S,S - diisopropyl - 2 - methoxyvinylphosphonodithioate.

3. A process of killing plants comprising applying to the plant habitat a herbicidally effective amount of a compound according to claim 1 having the formula 50

where R_1 , R_2 and R_3 are all alkyl groups of 1 to 4 carbon atoms.

4. A process according to claim 3 wherein the compound is applied to the soil prior to the emergence of the plant. 5

5. A process according to claim 4 wherein the compound is selected from the group consisting of S,S-diisopropyl-2-methoxyvinylphosphonodithioate; S,S-diethyl-2-ethoxyvinylphosphonodithioate; S,S-di-n-propyl-2-ethoxyvinylphosphonodithioate; S,S-diisopropyl-2-ethoxyvinylphosphonodithioate; and S,S-diisopropyl-2-isobutoxyvinylphosphonodithioate. 30

6. A process according to claim 3 wherein the compound is applied to the plants after the emergence of the plants.

7. A process according to claim 6 wherein the compound is selected from the group consisting of S,S-diisopropyl-2-methoxyvinylphosphonodithioate; S,S-diisopropyl-2-isobutoxyvinylphosphonodithioate; and S,S-dibutyl-2-isobutoxyvinylphosphonodithioate. 40

8. A process according to claim 3 wherein the compound is S,S - diisopropyl - 2 - isobutoxyvinylphosphonodithioate. 50
